UNITED STATES PATENT OFFICE.

HENRY C. MILLER, OF MILWAUKEE, WISCONSIN, ASSIGNOR TO H. C. MILLER COMPANY, OF MILWAUKEE, WISCONSIN, A CORPORATION OF WISCONSIN.

LOOSE-LEAF BINDER.

Application filed November 27, 1925. Serial No. 71,711.

This invention relates to improvements in loose leaf binders of that type in which the leaves are removably secured between adjustable side covers.

5 In binders of this type, it is customary to provide bindings posts which extend through perforations formed in the leaves for holding the leaves in place. In order to permit the insertion or removal of the leaves, one of 10 the covers is detachable from the post ends, and heretofore it has been found quite difficult to quickly connect the cover to the posts to lock the parts together, due to the fact that three or four posts are used, and it is difficult 15 to maintain the openings of the cover in alignment with the eyes of the posts to permit insertion of the locking pins.

It is one of the objects of the present invention to overcome the before mentioned objectionable features and provide a loose leaf binder in which the parts may be easily held in alined position to permit the insertion of the locking pins.

A further object of the invention is to provide 25 a loose leaf binder in which the covers may be swung to open position a sufficient distance to expose the entire writing surface of the leaves.

A further object of the invention is to provide 30 a loose leaf binder in which the locking posts are engaged in progressive order in moving the pins to locking position.

A further object of the invention is to provide 35 a loose leaf book which is of simple construction, is strong and durable, and is well adapted for the purpose described.

With the above and other objects in view, the invention consists of the improved loose 40 leaf binder and its parts and combinations as set forth in the claims, and all equivalents thereof.

In the accompanying drawing in which the same reference characters indicate the same parts in all of the views:

45 Fig. 1 is a sectional view of the loose leaf binder;

Fig. 2 is a detail view, on a larger scale, of the posts and the locking member;

50 Fig. 3 is a side view of the parts shown in Fig. 2;

Fig. 4 is a side view, on a large scale, of one of the binding posts;

Fig. 5 is a sectional detail view, on a large scale, of a portion of the binder showing the

manner of forming the connection, the cover 55 being shown in closed position; and

Fig. 6 is a similar view with the cover shown in open position.

Referring to the drawing, the numeral 8 indicates the flexible back and 9 the side 60 covers hinged thereto by flexible material 10, to permit the covers to be swung to open position. The inner sides of said covers have mounted thereon elongated hinge plates 11 to which the posts 12 are pivotally connected. 65 The inner or pivotal edge portions of the plates are bent over outwardly to form tubular portions 13 of rectangular form in cross-section for receiving reciprocable locking members 14. The inner edge parts of the 70 tubular portions are provided with spaced recesses 15 to receive the rounded and eyed ends 12' of the posts 12. The tubular portions are provided along the inner longitudinal edges of the recesses 15 with rearwardly 75 extending guide or locating spaced stops 16 and 16' which straddle and closely fit the rounded ends of the posts to hold the ends of the posts in alinement. The reciprocal locking members 14 have cut away portions 17 80 and locking pins 18 which are alined to extend through the eyes of the posts 12 to form pivotal connections therewith. For convenience in locking and unlocking the posts, the reciprocal locking members at one end 85 are bent at right angles to provide handles 19 which may be easily grasped to move the members to locked or unlocked position. In locking the posts it is only necessary to position the eyed post ends into the recesses 15 90 and then swing the cover to closed position and the guide lips 16 in swinging the cover will straddle and hold the ends of the posts so that when closed their eyes are in alinement with the pins 18 of the locking members, and it is only then necessary to push inwardly on the angled ends to lock the posts 95 to the cover.

To permit the covers to open to horizontal position, the rear side portions of the posts 100 adjacent the edges are recessed or notched as indicated by the numeral 20 to accommodate the lips 16 when the covers are turned to open position and which notches also first assist in aligning the posts.

The outer leaves of the binder are preferably provided with angular reinforcing strips 21 through which the posts 12 extend. Stop

pins 22 engaged by portions of the locking members limit the outward movement of the said locking members.

Particular attention is directed to the fact that the locking pins 18 progressively engage the eyed ends of the posts and that the pins are pointed to more easily enter the eyes of the posts. The progressive engagement is provided by making the pin 18 and the cut out portion 17 nearest to each handle the longest and then progressively reducing the length of each pin and cut-away portion, as clearly shown in Fig. 1 of the drawing, so that the pin nearest to the handle will engage the eye of the first portion and when partly entered, the next pin will enter the eye of the second post and thus continue until all of the posts are engaged.

From the foregoing description it will be seen that the loose leaf binder is of very simple construction and that the guide lips provide for the easy locking of the parts together.

What I claim as my invention is:

1. A loose leaf binder, comprising a pair of spaced covers, eyed posts connected to one of the covers and extending to positions adjacent the other cover, a hinge plate mounted on said last mentioned cover and having recessed edge portions and spaced stops projecting rearwardly from the side parts of the recessed portions of the hinge plate for guiding and locating the adjacent eyed ends of the posts after they have entered the recessed portions, and a reciprocable locking member carried by the hinge plate and having projecting portions for entering the eyed ends of the posts to pivotally connect the eyed ends to the plate.

2. A loose leaf binder, comprising a pair of spaced covers, eyed and recessed posts connected to one of the covers and extending to positions adjacent the other cover, a hinge plate mounted on said last mentioned cover and having a tubular edge portion formed

with spaced recesses and spaced stops projecting rearwardly from said recessed portions for guiding, locating and alining the adjacent eyed ends of the posts after they have entered the recessed portions, and a reciprocable locking member positioned within the tubular edge portions of the plate and having pin portions which enter the adjacent eyes of the posts to pivotally connect the posts to the hinge plate.

3. A loose leaf binder, comprising a pair of spaced covers, hinge plates mounted on each cover and having tubular edge portions formed with spaced recesses and spaced stops projecting rearwardly from said recessed portions, posts having eyed end portions which are limited in their relative movement and are guided by the spaced stops as they extend into the recesses, and reciprocable locking members positioned within the tubular portions of the plates and having pin portions of varying lengths which enter the adjacent eyes of the posts to pivotally connect the posts to the hinge plates between the stops.

4. A loose leaf binder, comprising a pair of spaced covers, eyed and notched posts connected to one of the covers and extending to positions adjacent the other cover, a hinge plate mounted on said last mentioned cover and having a tubular edge portion formed with spaced recesses and side stops projecting rearwardly from the recessed portions of the plate for guiding, locating and alining the adjacent eyed and notched ends of the posts after they have entered the recesses to aline the eyes of the posts, and a reciprocable locking member positioned within the tubular portion and having pin portions of varying lengths which progressively enter the adjacent eyes of the posts to pivotally connect the posts to the plate.

In testimony whereof, I affix my signature.

HENRY C. MILLER.
